CLAIM

The ornamental design for a medical percussion hammer or the like, substantially as shown and described.

DESCRIPTION

FIG. 1 is a front view of the medical percussion hammer or the like, the rear being a mirror image thereof; FIG. 2 is a side elevational view of one side of the percussion hammer;

FIG. 3 is an elevational view of the opposite side thereof;

FIG. 4 is a top plan view of the percussion hammer; and FIG. 5 is a bottom plan view of the hammer.
